Patented Feb. 24, 1920.

UNITED STATES PATENT OFFICE.

**HAROLD S. LOOMIS, OF WILKINSBURG, PENNSYLVANIA, ASSIGNOR TO THE UNION
SWITCH & SIGNAL COMPANY, OF SWISSVALE, PENNSYLVANIA, A CORPORATION
OF PENNSYLVANIA.**

RAILWAY SIGNALING.

1,331,514.

Specification of Letters Patent. Patented Feb. 24, 1920.

Application filed August 1, 1917. Serial No. 183,835.

To all whom it may concern:

Be it known that I, HAROLD S. LOOMIS, a citizen of the United States, residing at Wilkinsburg, in the county of Allegheny 5 and State of Pennsylvania, have invented certain new and useful Improvements in Railway Signaling, of which the following is a specification.

My invention relates to railway signaling. 10 One object of my invention is the provision, in combination with two signals operated by energy from a common source, of means for preventing simultaneous operation of the signals but for permitting the 15 operation of either signal immediately upon completion of the operation of the other. I thus avoid the necessity for two sources of energy, or for a common source of energy of sufficient capacity to operate the two signals 20 at the same time.

I will describe one form of signaling system embodying my invention, and will then point out the novel features thereof in claims.

25 The accompanying drawing is a diagrammatic view showing one form of signaling system having applied thereto one form of apparatus embodying my invention.

Referring to the drawing, A—B is a 30 stretch of single track between two passing sidings E and F, over which stretch traffic moves in both directions. Eastbound traffic through this stretch is governed by signals S', S³ and S⁵, located at intervals 35 through the stretch, while westbound traffic through the stretch is governed by signals S², S⁴ and S⁶, also located at intervals through the stretch.

The apparatus and circuits here shown 40 for the control of the signals are similar to the apparatus and circuits shown in Letters Patent of the United States granted to Ronald A. McCann on July 17, 1917, No. 1,233,488. Briefly described, the system is as 45 follows:

The stretch A—B is divided by insulated joints 3 into several successive sections, A—C, C—D and D—B, and, as here shown, a pair of opposing signals is located at each 50 juncture of adjacent sections, although I do not wish to be limited to this particular location of the signals. Each section is provided with one or more track circuits, including track relays, for the control of the 55 signals. As here shown, each section is

divided by insulated joints 3 into two sub-sections, and each subsection is provided with a separate track circuit. For example, section A—C is divided into two sub-sections A—H and H—C, the former sub-section being provided with a track circuit comprising a track battery b and a track relay T'. Each sub-section is similarly provided with a track circuit comprising the rails of the sub-section, a track battery b, and a 65 track relay, the relay being designated by the reference character T with the same exponent as that of the adjacent signal which governs traffic through the sub-section.

Each signal is provided with a signal relay for the control thereof, each of which relays is designated by the reference character R with an exponent corresponding to the exponent of the signal which the relay controls. Each signal relay (except relays R⁶ 70 and R⁵) is controlled by both track relays for the section through which the signal governs traffic, and also by a front contact of the signal relay corresponding to the signal next in advance governing traffic in the same 80 direction. For example, relay R³ which controls signal S³, is provided with a circuit from battery G⁵, through wire 4, contact 5 of relay R⁵, wires 6 and 8, contact 9 of relay T⁴, wire 10, contact 11 of relay T³, wire 12, 85 contact 7 of relay P⁶, wire 44, relay R³, wires 13 and 14, and common wire O to battery G⁵. The circuits for signal relays R', R⁴ and R², are similar to those just traced for relay R³. The circuits for signal relays R⁶ and R⁵ are 90 similar to that for relay R³, except that, as here shown, they are controlled only by the track relays for sections A—C and D—B, respectively, and by certain contacts on relays P⁸ and P⁴, respectively. 95

Each signal S is provided with controlling circuits governed by the corresponding relay R, whereby the signal indicates "proceed" or "stop" according as the relay is energized or deenergized. The control of these 100 signals by their relays is as follows:

Each signal is of a usual type, comprising a semaphore biased by gravity to the "stop" position, an electric motor M for moving the signal to "proceed" position, and a 105 holding device Q for holding or retaining the signal in the proceed position after it has been moved there by the motor.

The circuit for motor M of signal S³ is from the right-hand terminal of battery G³ 110

- through wires 31 and 32, contact 33 of relay R³, wire 34, motor M, wire 35, contact 36, wire 37, back contact 38 of a relay X³, wire 39, relay X³, wire 40, common wire O to the 5 left-hand terminal of battery G³. Contact 36 is operated by signal S³ and is closed in all positions of the signal except the "proceed" position, in which position it is open. It will be seen, therefore, that when relay 10 R³ is closed, motor M is operated to move signal S³ to the "proceed" position, provided that relay X³ is deenergized, and that the motor circuit becomes opened as soon as the signal reaches the "proceed" position.
- 15 The circuit for the holding device Q is the same as that for the motor up to and including wire 34, then it passes through wire 41, the holding device, wire 42, contact 43 of relay R³, and wire 14 to battery G³.
- 20 It will be seen, therefore, that after the signal has been moved to its "proceed" position it will be held there as long as relay R³ remains energized.
- The motor M and holding device Q for 25 signal S⁶ are also supplied with energy from battery G³, and the circuits for these instrumentalities are similar to those for the corresponding parts of signal S³. That is, the circuit for motor M of signal S⁶ is controlled by relay R⁶, contact 36 operated by the signal, and back contact 38 of relay X⁶, and this circuit includes relay X³. The circuit for holding device Q of signal S⁶ is controlled by relay R⁶.
- 30 Each relay X³ and X⁶ is energized to open its back contact when the motor circuit in which it is included is closed, and such relay then, of course, opens the motor circuit for the other signal. From this it 35 will be seen that the motors for signals S³ and S⁶ cannot be operated simultaneously.
- Assume now that for any reason both relays R³ and R⁶ are deenergized, so that both signals S³ and S⁶ are at "stop", and that 40 relay R³ then becomes energized. The circuits for the motor and holding device of signal S³ are then closed, so that the motor starts to move the signal toward its "proceed" position. Relay X⁶ thus becomes energized. If, during this movement of signal S³, relay R⁶ becomes energized, the circuit for motor M of signal S⁶ will not be closed because this circuit is open at contact 45 38 of relay X⁶. As soon, however, as signal S³ reaches its "proceed" position, contact 36 on this signal opens the circuit for the motor of the same signal, whereupon relay X⁶ becomes deenergized and so permits the circuit for the motor of signal S⁶ to be closed.
- 50 Signal S⁶ is then moved to the "proceed" position.
- The motor circuits for signals S⁴ and S⁵ are similarly controlled by relays X⁴ and X⁵.
- 55 It will be seen that, as thus far described,

as a train enters the stretch A-B from either end, all the signals governing traffic through the stretch in the direction opposite to that in which the train is moving will change to "stop" indication, and that as the train proceeds through the stretch the signals in its rear governing traffic in the direction in which the train is moving will change to "stop" indication as they are passed by the train and will remain at stop until the train leaves the stretch. Means are provided, however, for at times rendering each of the signal relays ineffective to control the signal relay for the signal next in the rear, so that as a train proceeds through the stretch the signals in the rear of the train may change to proceed indication when the train has left the portions of the stretch through which they immediately govern traffic, thereby permitting a following train to pass through the stretch at a safe distance from the first train. This means, as here shown, is a branch around the signal relay contact which controls the signal relay next in the rear, and this branch is controlled by a polarized relay located adjacent the signal relay. Each of these polarized relays is designated by the reference character P, with the same exponent as that of the signal relay around whose contact it forms a branch. Each relay P is responsive only to reversals of current, and having once responded to current of one direction its contacts remain in the position to which they have been moved even after the relay is deenergized and until it is energized by current in the opposite direction. Each polarized relay P is provided with a "normal" and a "reverse" energization circuit, which circuits are controlled by the adjacent track relay T, and also by a circuit controller K operated by the adjacent signal. For example, the normal energization circuit for relay P⁵ is from the middle point of battery G⁵, through wires 17 and 18, relay P⁵, wire 19, upper point of contact 20 of relay R⁵, wire 21, contact a of circuit controller K⁵ (operated by signal S⁵), wire 22, upper point of contact 23 of relay T⁵, wire 24, and wire 4 to right hand terminal of battery G⁵. This normal circuit is provided with a branch which extends from wire 19, through back point of contact 20, wire 25, contact d of circuit controller K⁵ to wire 22. The reverse energization circuit for relay P⁵ is from the middle point of battery G⁵, through wires 17 and 18, relay P⁵, wire 19, lower point of contact 20, wire 25, contact d, wire 22, lower point of contact 23 of relay T⁵, and wires 26 and 27 to the left hand terminal of battery G⁵. It is apparent that current flows through the winding of relay P⁵ in one direction or the other according as track relay T⁵ is energized or deenergized, provided that the circuit of re- 130

lay P^5 is closed through circuit controller K^5 and contact 20 of relay R^5 . Contact d of circuit controller K^5 is closed during a portion of the movement of signal S^5 from 5 "proceed" to "stop" or vice versa, but is opened when the signal is at either of these positions. Contact a is closed only when the signal is in the stop position.

Each polarized relay P is provided with 10 a normal and a reverse energization circuit, which circuits are similar to those just described for relay P^5 .

Current through relay P^5 in the normal direction causes contact fingers 7 and 16 to 15 swing to the right, while current in the reverse direction causes these fingers to swing to the left. The same is true of relay P^3 . To simplify the reading of the drawing, however, the connections to relays P^4 and P^6 20 are such that their contacts swing to the left when the current is normal, and to the right when the current is reverse.

The branch around contact 5 of relay R^5 , which is the contact which normally controls 25 relay R^3 , is from wire 4 through wire 15, contact 16 of relay P^5 , wire 28 to wire 6.

The operation of the apparatus during the passage of an eastbound car or train through the stretch A—B, is as follows:

30 When a train enters sub-section A—H, it opens track relay T' , thereby opening at contact 29 the circuit for relay R' , which in turn causes signal S' to change to the stop indication. The opening of contact 11 of 35 track relay T' opens the circuit for signal relay R^6 so that signal S^6 changes to the stop indication. The opening of relay R^6 opens at contact 30 the circuit for signal relay R^4 so that signal S^4 changes to stop, and the opening 40 of relay R^4 opens at contact 30 the circuit for relay R^2 so that signal S^2 likewise changes to the stop indication. As the train enters sub-section H—C, it opens track relay T^6 but this has no effect on the signals, because 45 contacts 11 and 29 of this relay control the same circuits as do contacts 11 and 29 of relay T' . As the train enters sub-section C—L, it opens track relay T^4 , thereby opening at contact 11 the circuit for relay R^8 , whereby signal S^8 changes to "stop." 50 As circuit controller K^3 , operated by signal S^8 , sweeps over contact d , the reverse energization circuit for relay P^8 becomes closed, so that the contacts of relay P^8 are reversed, 55 thus bridging the contact of relay R^8 in the circuit for relay R' . When the entire train leaves sub-section H—C, the closing of track relay T^4 closes the circuit for signal relay R' , so that signal S' then changes to proceed, 60 thereby permitting the following eastbound train to enter the stretch. The closing of track relay T^4 also closes at contact 11 thereof the circuit for relay R^6 , but this circuit remains open at contact 7 of relay P^8 , hence 65 signal S^6 continues to indicate stop. When

the train passes signal S^6 it places this signal at stop and reverse relay P^6 , in the same way that it previously affected signal S^3 and relay P^3 . Relay R^3 now closes because its circuit is closed at contact 16 of 70 relay P^5 , hence signal S^3 begins to clear. Immediately upon the closure of relay R^3 , the normal energization circuit for relay P^3 is closed so that the contacts of this relay swing back to the positions in which they are 75 shown in the drawing. This reversal closes at contact 7 the circuit for relay R^6 , thus closing at the contacts of this relay the circuit for signal S^6 . This signal circuit, however, is open at contact 38 of relay X^6 , which 80 relay was picked up by the closure of the motor circuit for signal S^6 , hence signal S^6 will not move until signal S^6 has reached the proceed position.

The circuit for relay R^4 being controlled 85 by relay R^5 , signal S^4 remains in the stop position while the train is in section D—B. As the train passes out of the stretch, relay R^5 closes, thus causing signal S^4 to move to the proceed position, and also energizing 90 relay P^5 in the normal direction. Relay R^2 now closes, but the circuit for signal S^4 remains open at contact 38 of relay X^4 until signal S^4 has reached the proceed position, whereupon signal S^4 changes to proceed. 95 Signal S^2 , of course, changes to the proceed position as soon as the train leaves the stretch. The parts of the apparatus are then again in the positions in which they are shown in the drawing. 100

The operation of the apparatus during the passage of an eastbound train through the stretch will be apparent from the operation just described during the passage of an eastbound train. 105

By providing the relays X^3 and X^6 to prevent simultaneous operation of signals S^3 and S^6 , I am enabled to operate both of these signals from one battery G^3 , which battery need be only of sufficient capacity to operate 110 but one of the signals at a time. This arrangement, therefore, reduces the initial cost of the battery, reduces the cost of renewals of the battery and reduces capacity of shelter which has to be provided for battery. These reductions in costs more than offset the increased cost of the system due to 115 the additional relays X^3 and X^6 . The same is, of course, true as to battery G^6 for signals S^4 and S^6 . 120

It may be well to add, by way of explanation, that the resistance of each holding device Q is high, so that the total current drawn from battery G^3 by these devices when both signals S^3 and S^6 are being held 125 in the "proceed" position is considerably less than the current required for the operation of one signal motor.

Although I have shown and described only one form of apparatus embodying my 130

invention, it is understood that various changes and modifications may be made therein within the scope of the appended claims without departing from the spirit and scope of my invention.

Having thus described my invention, what I claim is:

1. In combination, two signals, a source of current, an operating circuit for each signal including said source, means for opening each circuit upon completion of the operation of the corresponding signal, and means included in said operating circuits for preventing simultaneous operation of the two signals.
2. In combination, two signals each biased to stop position, a motor for each signal for moving the signal to a proceed position in opposition to its bias, a source of current, a circuit for each motor including said source, two relays one included in each circuit, each circuit also including a back contact of the relay in the other circuit, and means operated by each signal for opening the circuit for the corresponding motor when the signal has reached its proceed position.
3. In combination, two signals, a source of current, a circuit for each signal including said source, and two relays one included in each circuit, each circuit also including a back contact of the relay in the other circuit, whereby simultaneous operation of said signals by energy from said source is prevented.
4. In combination, two signals each biased to stop position, a motor for each signal for moving the signal to a proceed position in opposition to its bias, a source of current, a circuit for each motor including said source, means for opening each circuit upon completion of the movement of the corresponding signal to its proceed position, and means

included in said circuits for preventing simultaneous operation of the two motors.

5. In combination, two signals each biased to stop position, a motor for each signal for moving the signal to a proceed position in opposition to its bias, a source of current, a circuit for each motor including said source, means for opening each circuit upon completion of the movement of the corresponding signal to its proceed position, means for each signal for holding the signal in said proceed position, and means included in said circuits for preventing simultaneous operation of the two motors.

6. In combination, a single source of current, two signals operated by current from said source, a circuit for each signal, means for opening each circuit when the operation of the corresponding signal is completed, a contact in each circuit which contacts may be closed simultaneously, a second contact in each circuit, and means controlled by each circuit and operating when the circuit is closed for holding open the said second contact in the other circuit.

7. In combination, a single source of current, two signals operated by current from said source, a circuit for each signal, means for opening each circuit when the operation of the corresponding signal is completed, means for closing said circuits simultaneously at one point in each circuit, and means controlled by each circuit and operating when the circuit is closed for holding the other circuit open at a second point.

In testimony whereof I affix my signature in presence of two witnesses.

HAROLD S. LOOMIS.
